UNITED STATES PATENT OFFICE.

CHARLES D. KING, OF RUTHERFORD, NEW JERSEY.

APPARATUS FOR DRILLING AND THE LIKE.

Application filed April 26, 1922, Serial No. 556,682. Renewed July 10, 1926.

This invention relates to apparatus for drilling and like operations, and particularly to holding means for such operations. Its main object is to provide an apparatus which is adaptable for operations on a variety of pieces, and also to provide means to facilitate the operations of drilling and the like. Another object is to provide means for increasing production and for reducing labor in such operations.

In carrying out the above objects I provide apparatus which is substantially universal in holding a variety of pieces to be machined, and such apparatus includes a substantially universal frame, and one or more adjustable work-supporting means which are adaptable to a large number of pieces. I also provide tool-guiding means which can be mounted on the universal frame and changed from time to time to conform to different pieces. For increasing production, the frame is provided with two sets of work-supporting means, each of which sets may consist of one or several individual work-holders, and there are also two sets of tool-guiding means, one for each set of work-supporting means, so that a machining operation can be performed on a part or parts in one set while another part or set of parts is being removed and replaced by unmachined parts or blanks.

For accomplishing the above objects I prefer to employ the means illustrated in the drawings accompanying and forming part of this specification, and in which—

Figure 1 is a side elevation of my improved apparatus for drilling and the like.

Fig. 2 is a rear elevation of the same with a portion of a drilling machine table in section.

Fig. 3 is a plan of the apparatus shown in Figs. 1 and 2.

Fig. 4 is a detail side elevation of a modified form of a portion of my invention.

Fig. 5 is a detail front elevation of the same.

Fig. 6 is a detail plan partly in section of another modification of part of my invention.

Fig. 7 is a side elevation of the parts shown in Fig. 6.

Fig. 8 is a side elevation of another modification of a portion of my invention, and

Fig. 9 is a side elevation of a socket wrench for use on certain parts of my invention.

Like characters refer to like parts in all the figures of the drawings.

My improved apparatus may be mounted on the frame of a drilling or like machine in any suitable way, as for instance, on the table thereof. The said table may be of any suitable form, such as that indicated by the numeral 2 in Figs. 1, 2 and 3. The main portion of my improved apparatus is preferably a frame member such as that indicated by the numeral 3. Ordinarily the frame member has a base-plate such as indicated by 4, and when used with an upright drilling machine, has an upright portion or portions such as 5. Preferably there are overhanging portions 6 at the upper part, which may be provided with openings or slots such as 7. The frame member 3 may be mounted directly on the table 2, or may be mounted on intermediate portions, as illustrated in the drawings, and such intermediate portions preferably consist of two slides 8 and 9, at right angles to each other, so that the frame and the parts thereon can be moved to a great number of different positions in the same plane or level.

The frame member 3 is secured to the table, slide or other suitable support by any suitable means such as a pivot-pin 10, passing through a suitable hole in the supporting member, and held fast by a nut 11. To facilitate turning, a ball-bearing such as 12 may be employed. The upright portion or portions of the frame 3 are provided with vertical alining edges which are shown in Figs. 1, 2 and 6 in the form of T-slots 13.

Any suitable work-supporting members may be provided on the frame for supporting the blank parts to be machined, and I preferably employ angle blocks such as 14, which have alining portions 15 adapted to aline them in the T-slots 13. The said angle blocks are preferably movable up and down in said slots and have bolts 16, 17, and nuts 18, by means of which they can be clamped at any height within the limits of the T-slot. The nuts 18 can slide up and down in the said slots along with the angle blocks, and have suitable alining faces 19 to cause them to be alined with the sides of the T-slot. If desired, a spring-plunger such as 20 can be employed to locate the blocks 14 in a given position in the slot, suitable holes 21 being placed in the upright portion 5. While the work-supporting members are here shown as movable vertically into and

out of drilling position, they may, if desired, move in any suitable direction, as for instance, in a horizontal direction, when used in machines whose drilling or working spindles are horizontal.

Suitable holding means for blanks are placed on the upper part of the member or members 14, and these are preferably of a form to fit the part to be held, as in Fig. 1, where the part to be held is a circular plate 23 having a hub 24, and where the holding means embody a seat portion or block 25 on which the plate 23 rests, having a hole 26 for the hub 24, a pin 27 for alining with the hole in the hub and a clamping screw 28 to secure the hub 24. A wrench such as the socket wrench 30 of Fig. 9 is used to tighten the bolts 16, 17 and the clamping screw 28. To put a blank in position, the bolts 16, 17, are loosened, and the member 14 is lowered, the blank put in position with the hub in the hole 26, the screw 28 clamped on the hub, and the member 14 moved up to the position shown in Fig. 1 which is found by the spring plunger 20 meeting the hole 21, and the bolts 16, 17, are then tightened by the wrench 30.

Suitable guiding means for drills and other cutting tools are provided, ordinarily such means consisting of holes such as 33 in the plate or plates 34 mounted on the overhanging portions 6 of the frame 3, and held by suitable means such as screws 35 and dowel pins 36. A portion 37 of said plate 34 ordinarily extends down into the opening or slot 7, so that the tool-guides may be as close as possible to the blanks to be machined. For very accurate work the holes 33 will be in bushings 38 in the plate 34, as seen at the right in Fig. 2.

Besides the work-holding means shown in Fig. 1, other means may be employed, as in Figs. 4 and 5, where the seat portion or block 25 is provided with gibbs 40 and jaws 41 movable in said gibbs by a right and left hand threaded screw 42 so as to clamp the member 43 by its hub 44. Blanks of other forms are readily held by changes in the arrangement on the seat portion or block 25, as seen in Figs. 6 and 7, where a V-block 46 is secured to the block 25 and a screw 47, in a lug 48, clamps the blank 49, which is alined at the sides by pins 50. Also in Fig. 8 the seat portion 25 has a groove 51, in which the blank 52 fits, and is secured by a clamp 53 and a bolt 54.

The work-holder frame 3 can be turned about the pin 10 by loosening the clamping bolts 57 and clamps 58, and pulling up and giving a quarter turn on the spring-plunger 59. In ordinary use a set of parts to be machined are clamped in proper position on the work-supports 14 at the front of the apparatus (on the left side of Fig. 1). The frame 3 is then turned one hundred and

eighty degrees to bring the blanks and tool-guides under the drills D or other cutting tools, as seen at the right in Fig. 1. The spring-plunger 60 is then let down into the hole 84', and the bolts 57 tightened on the clamps 58 to hold the frame 3 and parts thereon firmly in position on the supporting means.

This apparatus may be employed on various machines in common use such as two spindle drilling or milling machines, four spindle drilling or milling machines, and multi-spindle machines of the same type. If a four spindle type of machine is used, the slides 8 and 9 are moved by means of a crank or hand-wheel applied to the shanks of the screws 64 and 65, so as to shift the frame 3 and parts thereon to different positions, employing the pointers 70 and scales 71, or spring-plungers 75 and holes 76 to locate such positions, and drilling or otherwise machining, four holes or other operations for each downward movement of the drills or tools. If the drill feed is hand operated, one operator will be required to attend to it, and one operator will meanwhile remove drilled pieces and put fresh blanks in place on the work-supports at the front of the apparatus or at the left side in Fig. 1. Substantially the same method holds for the two spindle machines with slightly more shifting of the slides 8 and 9. If the machine used is provided with a power feed, one operator can advantageously attend to all operations of placing and removing blanks, and starting and stopping the feed of the tools, at a great saving in labor cost and relative increase of production.

If a multiple spindle machine with power feed is used, the greatest efficiency and economy can be obtained, as in the work shown in Figs. 1, 2 and 3; twenty-four holes can be drilled in one setting, and if the holes are short in depth, two operators can be employed for handling blanks, one of whom starts the feed and otherwise controls the cutting tools.

It will be noted that only a single frame member 3 is necessary for supporting all sorts of blanks up to a certain size so that I term the frame universal in this respect, and I also term the member 14 upon which are mounted the means to secure the blanks, universal for a similar reason. The said member 14 as described hereinbefore is adapted to be lowered from the drilling position, so that more room can be had for taking out and putting blanks into the seat portion, and it can be raised when the blanks are in place, up to a position close under the drill guides. The clamping bolts are made of a sufficient size to allow it to be rigidly clamped in such position.

The layout of the screw and pin holes in

the plates 34 is interchangeable for all layouts of drill or tool-guides so that the frame 3 and the work-supports 14 are used in common or are universal to a large variety 5 of drill-guide plates.

All the spring-plungers operate on the same plan, of which the plunger numbered 60 is representative and will be now described. The movable part of said spring 10 plunger is indicated by 80, and moves up and down in a threaded bushing 81, secured to the plate 4. A coil spring 82 is placed between the collar 83 of the member 80 and the top part of the bushing so that the member 80 is normally pressed towards the hole 84. There is a pin 85 on the member 80 which can pass up or down through the slot 86 in the top part of the bushing 81 when the member 80 is moved up or down, and 15 when the member 80 is moved up and given a quarter turn it will remain up by reason of the pin 85 resting on the top part of the bushing 81.

Some operations can be performed in the 20 above described apparatus without the aid of the tool-guiding means such as that in the plates 34. In such cases the said plates 34 are removed and the apparatus used in all other respects as hereinbefore described for 25 changes in position of the parts to be machined.

It is evident that the mere mechanism 30 for giving the several movements to the different parts may be modified and changed in various ways, and any suitable forms of parts 35 and arrangement thereof may be employed without departing from the principle of the invention, and I do not therefore confine myself to the details of construction 40 here shown.

What I claim is:—

1. An apparatus for drilling and the like 45 embodying a separate fixture-frame adapted to be secured in alinement with a drilling spindle, drill-guiding means fixed on the fixture-frame, a work-support movable toward and from the drill-guiding means and guided by means on the fixture-frame, means to secure blanks to the said work-support, and means to secure the work support on 50 said fixture-frame immediately adjacent to the drill-guiding means for drilling and in a removed position on the fixture-frame for loading and unloading blanks.

2. An apparatus for drilling and the like 55 embodying a work-holder frame having a base-plate and ways substantially at right angles thereto, means for mounting the work-holder frame on the platen of a drilling machine alined to the drilling spindle thereof, drill-guiding means fixed to the upper part of the work-holder frame, and work-holding means on the work-holder frame and means to secure said work holding 60 means in their drilling position imme-

diate beneath the drill-guiding means and also to be moved along the ways of the work-holder frame away from said means to a lower position for inserting and removing blanks.

3. An apparatus for drilling and the like 70 embodying a work-holder frame adapted to be secured on the platen of a drilling machine alined to the drilling spindle thereof and provided with a portion having a T-slot 75 parallel to the spindle of the drilling machine, drill-guiding means secured to the outboard part of the work-holder frame, a work-support movable along said T-slot under said means, means to secure a blank 80 on said support, and means including a bolt and nut to secure the work-support in different positions along said T-slot.

4. An apparatus for drilling and the like 85 embodying a work-holder frame adapted to be secured on a drilling machine frame alined to the drilling spindle thereof and having a base-plate, an upright portion joined to the base-plate, and an overhanging portion secured to the upper part of the upright 90 portion, a plate having a tool-guide and secured to the overhanging portion, a work-support movable vertically on said upright portion of the work-holder frame, means to secure blanks on the work-support, and means to secure said work-support in its 95 uppermost position thereon during the machining period and also in a lower position for loading and unloading blanks.

5. An apparatus for drilling and the like 100 embodying a work-holder frame having a base-plate, an upright portion at the middle of said base-plate, and overhanging portions at the upper part on each side of the upright 105 portion, plates having drill-guides, one of which plates is secured to each of said overhanging portions, work-holding means under each of said plates and each including a member movable vertically on the upright portion and means to secure the vertically-movable member close to its respective drill-guide for drilling and in a lower position for loading and unloading blanks, a pivot-pin for pivoting the work-holder 110 frame on a drilling machine frame in alinement with the tool spindle thereof, and means to clamp said work-holder frame on said machine frame in two positions, one for drilling and one for loading and unloading 115 blanks.

6. An apparatus for drilling and the like 120 embodying a frame, means to position and secure the frame on a drilling machine alined to the drilling spindle thereof in two different positions substantially at one hundred and eighty degrees to each other, the position nearest the drilling machine frame for drilling and the other position for loading and unloading blanks, drill-guiding means in two sets, one set for each of said 125 130

frame positions, and work-holding means also in two sets, one set for each of said frame positions, and means to cause relative shifting between the drill-guide axes and the 5 drill axes.

7. An apparatus for drilling and the like embodying a work-holder frame, means for mounting the work-holder frame on a drilling machine frame or the like in alinement 10 with the tool spindle thereof, means for clamping said work-holder frame on said machine frame in two different positions the position nearest the drilling machine frame for drilling and the other position for loading and unloading blanks, a plurality of tool-guiding means secured to the work-holder frame in two sets, one set for each position, and a plurality of work-holding means on 15 said work-holder frame also in two sets, one set for each of the said positions.

8. An apparatus for drilling and the like embodying a work-holder frame having a base-plate, and upright portion at the middle part of the said plate, and overhanging 20 portions at the upper part on each side of the middle portion, tool-guide plates secured on said overhanging portions and provided with tool-guides, work-supports on said work-holder frame upright portion, one under each tool-guide plate, means to secure 25 blanks to said work-supports, a pivot-pin through the central part of said work-holder frame for pivoting it on a drilling machine frame in alinement with the tool spindle 30 thereof, and means to clamp the work-holder frame to said drilling machine frame in two different positions.

9. An apparatus for drilling and the like embodying a work-holder frame having a 40 base-plate, an upright portion at the middle part thereof and provided with vertical T-slots on each side, and overhanging portions at the upper part on each side of said middle portion, drill-guiding means on said overhanging portions, one set on each of said 45 portions, work-supporting members held by means of said T-slots, means to secure blanks to said work-supporting members, a pivot for pivoting the work-holder frame to the 50 frame of a drilling machine, and means to clamp the work-holder frame in alinement with the tool spindle thereof to said machine frame in two different positions.

10. An apparatus for drilling and the like 55 embodying a work-holder frame having a base-plate, an upright portion at the middle part of said base-plate, and overhanging portions at the upper part on each side of the upright portion and provided with slots, drill-guide plates having drill-guides secured on said overhanging portions over 60 said slots, work-holding means under each of said drill-guide plates, a pivot-pin for pivoting the work-holder frame on a drilling machine frame in alinement with the 65

tool spindle thereof, and means to clamp said work-holder frame on said machine frame in two different positions.

11. An apparatus for drilling and the like embodying a work-holder frame adapted 70 for alinement with a drilling spindle having a base-plate, an upright portion thereon, and an overhanging portion on the upright portion, drill-guiding means on the overhanging portion which include a plurality 75 of drill-guides, work-supporting means on said frame movable toward and from said drill-guiding means, and means to shift said parts in a given plane which includes two slides at right angles to each other, and means for moving each of them to and fro. 80

12. An apparatus for drilling and the like adapted to be secured in alinement with a drilling spindle and embodying a work-holder frame having a base-plate, a portion at its middle part substantially at right angles thereto, and overhanging portions at the outboard part of the right angle portion, a plurality of tool-guiding means on said overhanging portions, one set for each such 90 portion, a plurality of sets of work-holding means on said frame, one set for each set of tool-guiding means and movable toward and from the same, means to move the work-holder frame to different positions, one such position for each set of tool-guiding means and its accompanying set of work-holding means, and means to shift said parts to bring the work to be machined to different 95 centers.

13. An apparatus for drilling and the like adapted to be mounted on a drilling machine in alinement with the drilling spindle and embodying a work-holder frame having a base-plate, a portion at its middle part at right angles thereto and overhanging portions at the outboard part of the right angle portion, a plurality of sets of tool-guiding means on said overhanging portions, one set for each such portion, a plurality of sets 105 of work-holding means on said frame, one set for each set of tool-guiding means and movable toward and from the same, means to swivel the work-holder frame to different positions, one for each set of tool-guiding means and its cooperating set of work-holding means, and means to secure said frame in such positions which means include 110 sockets and a movable device to engage with said sockets.

14. An apparatus for drilling and the like embodying a work-holder frame adapted for alinement with a drilling spindle, having a part, and overhanging portions at the upper part one on each side of the upright portion, tool-guiding means on each of the overhanging portions, a plurality of work-supporting means on said frame in two sets, a set 125 under each set of tool-guiding means and movable toward and from the same, support 130

ing means for said frame including means to shift said frame and work-supporting means thereon to a plurality of positions in substantially the same plane to bring the blanks to be machined to different tool centers and which supporting means include two slides at right angles to each other and means to move them to and fro, and means to secure the work-holder frame on its supporting means in two different positions, one for each set of work-supporting means.

15. An apparatus for drilling and the like embodying a work-holder frame adapted to be alined to a drilling spindle and secured in such position, a plurality of sets of drill-guiding means respectively alined to a plu-

rality of cooperative sets of work-holding means, which alined sets of drill-guiding means and work-holding means are movable relatively toward and from each other, respectively into the drilling position, and the unloading and loading position, and means for moving such alined cooperating sets in a direction substantially at right angles to the drilling spindle to the drilling position and out of the latter to the unloading and loading position.

Signed at New York, in the county of New York, and State of New York, this 25th day of April, 1922.

CHARLES D. KING.
